(57) **CLAIM**

We claim the ornamental design for a control panel for medical refrigerator, as shown and described.

DESCRIPTION

FIG. 1 is a perspective view of a control panel for medical refrigerator of the present invention;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom view thereof;

FIG. 8 is a perspective view thereof shown in an environment;

FIG. 9 is a front view thereof shown in an environment;

FIG. 10 is a rear view thereof shown in an environment;

FIG. 11 is a left side view thereof shown in an environment;

FIG. 12 is a right side view thereof shown in an environment;

FIG. 13 is a top plan view thereof shown in an environment; and,

FIG. 14 is a bottom view thereof shown in an environment. The broken lines show parts of the controller for medical refrigerator that represent unclaimed subject matter and form no part of the claimed design.

1 Claim, 11 Drawing Sheets
